UNITED STATES PATENT OFFICE.

THEODORE JONATHAN WINT, OF FORT LEAVENWORTH, KANSAS.

RIDING-SADDLE.

SPECIFICATION forming part of Letters Patent No. 320,522, dated June 23, 1885.

Application filed April 2, 1885. (No model.)

To all whom it may concern:

Be it known that I, THEODORE J. WINT, Fourth Cavalry, United States Army, a citizen of the United States, residing at Fort Leavenworth, in the county of Leavenworth and State of Kansas, have invented a new and useful Improvement in Riding-Saddles, of which the following is a specification, reference being had to the accompanying drawings.

10 My invention relates to an improvement in riding-saddles; and it consists in a saddle having the side bars connected at the pommel and cantle by means of curved arms forming an arc of a circle, and that slide in a line with each other, so that the side bars of the saddle may be adjusted to any desired angle, and thereby adapted to fit the horse's back, and means for securing the curved arms together when the requisite adjustment has been attained, as will be more fully set forth herein-after.

15 In the accompanying drawings, Figure 1 is a perspective view of a McClellan saddle with my improved adjusting devices applied thereto. Fig. 2 is a front elevation of the same. Figs. 3 and 4 are elevations of modified forms of my adjusting arms.

20 A represents a saddle-tree, of which B represents the side bars, C the pommel, and D the cantle. The portions of the pommel and cantle above the space between the upper edges of the side bars are cut away, as shown, and the side bars are connected together by semicircular arms *a* that are formed with foot-plates *b*, and secured to the side bars of the saddle-tree by means of bolts, rivets, or screws. Two pairs of these curved arms are used for each saddle, one pair being secured to the side bars at the pommel, and the other pair being secured to the side bars at the cantle. These curved arms bear against and slide upon each other, and are provided with slots *a'* in their ends. A bolt or stud, *a'*, projects from each of the arms and enters the slot of the opposing arm. Nuts *a'* are screwed on the projecting ends of the bolts or studs, and serve to clamp the arms together, so as to render them immovable when the proper adjustment of the side bars has been attained.

25 40 45 50 By means of the semicircular sliding arms it will be understood that the side bars while being adjusted will move from the axis at *z*,

changing the angle of the bearing-surfaces of the bars to each other from their axis, each of the side bars having a turning motion from or on the upper edge of its bearing-surface, by this means causing the angles of the bearing-surfaces of the side bars to correspond with those of the horse's back without materially opening or closing the space between the upper edges of the side bars.

55 60 My improved adjusting devices are also well adapted to be applied to pack-saddles, and effect the same result and operate in the same way.

65 70 I am aware that it has been heretofore proposed to connect the side bars of a saddle together by means of arms adapted to slide in a line with each other, so as to adjust the side bars laterally, and widen or narrow the space between them, and this I disclaim.

75 80 85 My invention differs from this in that the connecting-arms are curved to form the true arc of a circle, and by this construction I am enabled to adjust the side bars of my saddle to any desired angle without materially widening or narrowing the space between the inner upper edges of the side bars, and thus adapt the bearing-surfaces of the side bars to the angles of the animal's back, which is necessary in order to fit the saddle to the back.

Having thus described my invention, I claim—

1. A saddle having side bars hinged together at the pommel and cantle by curved arms forming an arc of a circle, and that slide in a line with each other, to enable the side bars to be adjusted to any requisite angle, the pivotal points or axis being on a line with the upper edges of the bearing-surfaces of the side bars, and means for clamping the curved arms together, substantially as described.

85 90 95 2. The combination of the side bars, B, and the curved arms *a*, forming an arc of a circle, and adapted to work in a line with each other and adjust the side bars, substantially as described.

In testimony that I claim the foregoing as my own I have hereto affixed my signature in presence of two witnesses.

THEODORE JONATHAN WINT.
